UNITED STATES PATENT OFFICE

2,328,818

CIRCUIT INTERRUPTING APPARATUS

Sigurd I. Lindell and Anthony Van Ryan, Chicago, Ill., assignors to Schweitzer & Conrad, Inc., Chicago, Ill., a corporation of Delaware

Application August 1, 1940, Serial No. 349,264

23 Claims. (Cl. 200—114)

This invention relates, generally, to circuit interrupters and it has particular relation to fuse devices.

An important object of this invention is to provide for positive arc interruption and positive dropout action in a fuse construction in which the fuse link is definitely tensioned and arcing at the contact members is avoided during arc interruption.

An object of this invention is to provide for installing a fuse link in a fuse tube under little or no tension and then for tensioning the fuse link in a predetermined amount in a new and improved manner.

Another object of this invention is to provide for tensioning a fuse link in a fuse tube during the movement thereof to the circuit closed position in a new and improved manner.

A further object of this invention is to provide for moving apart a pair of members carried by a fuse tube and biased toward each other to tension a fuse link previously installed in the fuse tube under little or no tension.

A still further object of this invention is to provide for striking a blow on a toggle mechanism supporting a fuse tube in the circuit closed position in order to positively unlock the toggle.

Another object of this invention is to hold a fuse link extracting member stationary with respect to a fuse tube while it is being moved on a support to circuit closed position and at the same time to hold an operating member stationary with respect to the support in order to tension a fuse link in the fuse tube and to extract a portion of it when the fuse link blows.

Still another object of this invention is to employ the stress applied in tensioning a fuse link to increase the contact pressure with a line terminal.

A further object of this invention is to provide a shock absorber action to the recoil of a fuse tube when the fuse link therein blows.

It is another object of the invention to provide for guiding a fuse tube into engagement with an upper line terminal by means on the lower line terminal in a new and improved manner.

A still further object of this invention is to provide for closing and opening a transfer switch in a repeating fuse construction by the movement of a dropout fuse to open circuit and closed circuit positions, respectively in a new and improved manner.

Other objects of this invention will, in part, be obvious and, in part, appear hereinafter.

Accordingly, this invention is disclosed in the

embodiments thereof shown in the accompanying drawings, and it comprises the features of construction, combination of elements and arrangement of parts which will be exemplified in the constructions hereinafter set forth, and the scope of the application of which will be indicated in the appended claims.

For a more complete understanding of the nature and scope of this invention, reference may be had to the following detailed description, taken in connection with the accompanying drawings, in which:

Figure 1 is a view, in side elevation, of a dropout fuse device embodying the present invention;

Figure 2 is a view, in front elevation, of the fuse device shown in Figure 1;

Figure 3 is a longitudinal sectional view of the fuse tube, together with the associated parts, separate from the mounting therefor;

Figure 4 is a longitudinal sectional view of a fuse link that may be employed in practicing the present invention;

Figure 5 is a detail view, certain parts being shown in section, showing the relationship of the fuse link extracting and toggle breaking means after the fuse link has blown and before any movement of the fuse tube has begun;

Figure 6 is a view, partly in side elevation and partly in section, showing the position assumed by the fuse tube and the parts associated with the toggle mechanism shortly after the toggle has been broken;

Figure 7 is a perspective view of the lower line terminal assembly;

Figure 8 is a perspective view of the lower fuse tube terminal and toggle mechanism associated therewith;

Figures 9 through 13 are perspective views showing the parts making up the toggle and fuse link extracting mechanism generally in the relative positions which they occupy when the fuse link has been installed in operative position in the fuse tube;

Figure 14 is a view, in front elevation, of a repeating fuse construction employing the dropout fuse unit shown in Figure 1 as a part thereof;

Figure 15 is a detail sectional view horizontally through one of the insulators, showing in further detail how the insulators are mounted on a support;

Figure 16 is a view, partly in side elevation and partly in section, showing the arrangement of the transfer switch mechanism;

Figure 17 is a detail sectional view taken along the line 17—17 of Figure 16; and

Figure 18 is a detail sectional view taken along the line 18-18 of Figure 16.

Referring now particularly to Figures 1, 2 and 3 of the drawings, it will be observed that the reference character 1 designates, generally, a dropout fuse device which is intended for use on electric power distribution circuits operating at voltages ranging upwardly from 2300 volts. Ordinarily, the dropout fuse device 1 will be employed in connection with a distribution transformer and will be connected between its primary winding and the line. Obviously, other uses may be made of the dropout fuse device 1 and, accordingly, it will be understood that its use is not limited to the application stated.

The dropout fuse device 1 comprises a single insulator 2 which may be a hollow porcelain insulator. Intermediate its ends the insulator 2 is provided with a metallic band 3 which is clamped by bolts 4 and 5 to it and to a bracket 6 having an arm or extension 7 for mounting the device as a unit on a crossarm or pole, as will be understood. The details of construction of the clamp band 3 and bracket 6 are set forth in the copending application of Triplett and Lindell, Serial No. 302,986, filed November 6, 1939, now Patent No. 2,255,400, issued Sept. 9, 1941.

At its upper end the insulator 2 is provided with a clamp band 8, similar to the clamp band 3, on which is mounted an upper line terminal, shown generally at 9, by means of bolts 10 and 11. The upper line terminal 9 includes an upwardly extending arm 12 having an integrally formed rib 13 to which may be secured a conductor clamp for connecting one of the line conductors thereto.

At its lower end the insulator 2 is provided with a metallic clamp band 14 for supporting a lower line terminal, shown generally at 15, by means of a bolt 16 and screws 17. The lower line terminal 15 is provided with an integrally formed rib 18 for receiving a conductor clamp for connecting the other line conductor to the lower line terminal 15.

The upper and lower line terminals 9 and 15 are arranged to be interconnected by a dropout fuse device, shown generally at 21. The dropout fuse device 21 comprises a fuse tube 22, Figure 3, formed by an outer sleeve 23 of weather-proof material, such as a phenolic condensation product, and an inner liner 24 formed of material such as fiber, or paper impregnated with magnesium borate, that is adapted to evolve an arc extinguishing medium due to the heat of an arc drawn incident to the operation of the device.

The fuse tube 22 is provided at its upper end with an upper fuse tube terminal, shown generally at 25. The terminal 25 includes a metallic ferrule 26 that can be secured to the upper end of the fuse tube 22 by transversely extending pins 27. An operating eye 28, Figure 1, is integrally formed with the ferrule 26 for receiving the prong of a switch stick for operating the fuse device 21 to the circuit closed position. A cap 29 is threaded on the upper end of the ferrule 26 and it is provided with a generally spherically shaped contact engaging portion 30 for interfitting with a correspondingly shaped recess 32 in a sleet hood 33 which forms a part of the upper line terminal 9.

The sleet hood 33 is rockably mounted on a pin 34 which extends through a body portion 35 of the upper line terminal 9 with which the upwardly extending arm 12 is integrally formed and

through which the bolts 10 and 11 extend. In order to limit the movement of the sleet hood 33 it is provided with a circular opening 36 in a rear wall 37 thereof through which projects a stop 38 that is integrally formed with the body portion 35 of the upper line terminal 9. It will be observed that the stop 38 limits both the upward and downward rocking movements of the sleet hood 33 on the pin 34.

With a view to shunting the pin connection between the sleet hood 33 and the body portion 35 of the upper line terminal 9, and to provide for biasing the former downwardly, a flexible strip 39 of good conducting material, such as copper, reinforced by a strip 40 of spring metal, is provided. The conducting and spring strips 39 and 40 are secured by rivets 41, only one of which is shown, to the sleet hood 33. At their other ends the strips 38 and 39 bear against a ridge 42 integrally formed in the body portion 35 of the upper line terminal 9.

Entry of the upper fuse tube terminal 25 into the sleet hood is facilitated and it is guided into position by the outwardly flared sides 43 and the upwardly flared top 44 of the sleet hood 33. Flanges 45, integrally formed with the ferrule 26 and extending laterally therefrom are provided to engage either of the outwardly flared sides 43 for centering the fuse device 21 with respect to the sleet hood 33 so as to insure proper seating of the contact engaging portion 30 in the recess 32 of the sleet hood 33 in the circuit closed position.

The fuse tube 22 is adapted to receive a replaceable fuse link which is shown generally at 46. The fuse link 46 may be of any of the types of universal link now on the market, the particular type shown being that illustrated and described in Ramsey Patent No. 2,144,707.

In Figure 4 of the drawings, the details of construction of the fuse link 46 are more clearly shown. As there indicated, the fuse link 46 is provided with relatively infusible terminals 47 and 48 which are interconnected by a relatively high strength strain wire 49 and a fusible element 50. The strain wire 49 may be a nickel alloy wire, while the fusible element 50 may be formed of silver. An insulating sleeve 51 is secured to the terminal 47 and projects over the terminal 48, out of which sleeve the terminal 48 is freely movable. The terminal 47 is provided with a threaded portion 52 for receiving a flanged sleeve 53. Underneath the flange of the sleeve 53 there is a washer 54 which is of sufficient diameter to fully cover and properly seat on the upper end of the ferrule 26, as shown in Figure 3 of the drawings. Secured to the terminal 48 is a flexible lead 55 which is of sufficient length to extend out of the lower end of the fuse tube 22 for connection to a lower fuse tube terminal, shown generally at 56, Figure 3. It will now be understood that the fuse link 46 serves to interconnect the upper fuse tube terminal 25 and the lower fuse tube terminal 56. It will also be understood that these fuse tube terminals 25 and 56 are arranged to have contact engagement with the upper and lower line terminals 9 and 15, respectively, for interconnecting the line conductors.

In Figures 1, 2 and 3 of the drawings certain of the details of the lower fuse tube terminal 56 are shown. It will be noted that it comprises a sleeve 57 which may be secured to the lower end of the fuse tube by transverse pins 58. It also includes a toggle and fuse link tensioning and ex-

tracting mechanism that is shown generally at 59. The mechanism 59 is pivotally mounted, by means of a pin 60, between the rearwardly projecting ears 61 from the sleeve 57 that are integrally formed therewith.

The mechanism 59 includes a toggle member 62, Figure 9, through which the pin 60 extends for pivotal mounting between the ears 61. The toggle member 62 is also provided with integrally formed outwardly extending trunnions 63 which are arranged to enter and rotate in upwardly opening U-shaped terminal receiving portions 64, Figure 7, in the housing forming the lower line terminal 15. The trunnions 63 serve to pivotally mount the dropout fuse device 21 as a unit, and it is about their axes that the fuse device 21 is rotated to the circuit closed position with the fuse link 46 installed therein.

The toggle member 62 is also provided with a pair of rearwardly extending projections 65 for engagement with contact fingers 66 which are backed up and urged forwardly by means of leaf spring strips 67. The contact fingers 66 and leaf springs 67 are secured to the lower line terminal 17 by means of suitable rivets 68.

The toggle member 62 is also provided with a threaded stud 69 around which the flexible lead 55 may be placed and clamped securely to the toggle member 62 by means of a nut 70.

As will be presently set forth, when the link 46 blows, the dropout fuse device 21, which is normally latched to the upper line terminal 9 because of the interfitting engagement between the spherical portion 30 of the cap 29 and the complementary concave portion 32 in the sleet hood 33, drops to the open circuit position. In order to limit the swing of the dropout fuse device 21 after it is released from latching engagement with the upper line terminal 9, the lower line terminal 15, Figure 7, has a generally U-shaped recess 71 in its lowermost portion the bottom of which is engaged by the sleeve 57 and acts as a stop therefor.

Integrally formed with the toggle member 62 is an eye 73 for receiving the prong of a switch stick. In order to place the dropout fuse device 21 into operative position, the prong of the switch stick is inserted in the eye 73 and then the fuse device 21 is lifted to such position that the trunnions 63 are above the U-shaped slots 64 in the lower line terminal 15. The fuse device 21 is then lowered until the trunnions 63 engage the bottom of these slots. The prong of the switch stick is then removed from the eye 73 and is inserted in the eye 28 to swing the fuse device 21 to the circuit closed position, as shown in Figure 1.

The relationship of the toggle member 62 with respect to the fuse tube 22 is such that, in the circuit closed position, a locked or over-center toggle arrangement is provided. As shown in Figure 1 of the drawings, in the circuit closed position the pivot axis of the toggle member 62 about the pin 60 is located slightly past a line 74 interconnecting the reaction point 76 at the upper end of the fuse tube 22 and the axes of the trunnions 63 about which the toggle member 62 pivots with respect to the lower line terminal 15. Since the axis of the pin 60 occupies this position, the downward force on the fuse tube 22 exerted by the leaf spring 40 in urging the sleet hood 33 downwardly, acts to hold the toggle in the locked or over-center position. When the fuse link 46 blows, it is then necessary to move the toggle member 62 past the center position along the line 74 in order to break the toggle

and permit the fuse tube 22 to swing to the open circuit position.

It is also desirable to provide for applying a predetermined tension to the fuse link 46 so that it will always be stressed to a certain extent which is independent of any action that is taken on the part of the lineman when the fuse device 21 is re-fused. Also, it is an advantage to be able to connect the fuse link 46 in place in the fuse device 21 so as to interconnect the upper and lower fuse tube terminals 25 and 56 initially under little or no tension. It is then unnecessary for the lineman, in re-fusing the fuse device 21, to hold any spring members in stressed condition while he is fastening the free end of the flexible lead 55 in place.

Accordingly, the mechanism 59 has been provided which not only permits the fuse link 46 to be placed in operative position in the fuse device 21 under little or no tension, but also it permits tensioning of the fuse link 46 in a predetermined amount and further provides for striking the toggle member 62 with a hammer blow in order to release it from the locked toggle position.

Referring now particularly to Figures 9, 11 and 12 of the drawings, it will be observed that the toggle and fuse link tensioning and extracting mechanism 59 comprises essentially three members. One of these members is the toggle member 62, Figure 9, which is pivoted on the ears 61 extending from the sleeve 57 on the lower end of the fuse tube 22 and is also pivoted in the upwardly opening U-shaped slots 64 in the lower line terminal 15. The trunnions 63, which rotatably mount the toggle member 62 on the lower line terminal 15, are apertured to receive a pin 77, Figure 10. On this pin 77 there are positioned a fuse link extracting member 78, Figure 11, and an operating member 79, Figure 12. It will be noted that these members 78 and 79 rotate about the same axis as does the toggle member 62 with respect to the lower line terminal 15.

The fuse link extracting member 78 is provided with an arm 80 which is long enough to extend slightly past the center of the bore of the fuse tube 22, as shown in Figure 1, and has a groove 81 in its under surface for receiving the flexible lead 55. When installed, the fuse link 46, with the flexible lead 55 clamped to the toggle member 62 by the clamp nut 70, holds the fuse link extracting member 78 stationary with respect to the fuse tube 22, regardless of its position. Integrally formed with the arm 80 is a hub 82 through which the pin 77 extends. A hammer member or arm 83 is integrally formed with the hub 82 of the fuse link extracting member 78 and is arranged to strike an anvil member or flange 84 which depends from the underside of the toggle member 62, as shown more clearly in Figure 5 of the drawings. When the fuse link 46 blows, the fuse link extracting member 78 is released and, as will be presently apparent, it is urged with considerable force in a clockwise direction, as viewed in Figure 5 of the drawings. This movement of the fuse link extracting member 78 performs two functions. First, it rapidly withdraws the remaining portion of the flexible lead 55 so as to quickly separate the terminal 48, Figure 4, from the terminal 47 and extend the arc therebetween. Next, the hammer portion 83 strikes the anvil or flange 84 of the toggle member 62 with considerable force, and serves to break the toggle joint by causing the toggle member 62 to move in a clockwise direction so that the axis of the pin 60 moves from the over-center position,

Figure 1, past the line 74, where gravity and the downward biasing force applied to the sleet hood 33 are effective to cause further movement of the fuse device 21 to the open circuit position.

The operating member 79 is provided with a pair of spaced-apart apertured ears 86, Figure 12, through which the pin 77 extends. These ears 86 are provided with extensions or shoulder portions 87 which are arranged to engage shoulder portions 88, Figure 7, integrally formed with the housing of the lower line terminal 15 directly underneath the upwardly opening U-shaped slots 64. A web 89, integrally formed with the ears 86, serves to rigidly interconnect them.

It will now be apparent that the fuse link extracting member 78 and the operating member 79 are coaxially mounted within the toggle member 62 and that they are movable relative to each other. With a view to biasing these members for rotation toward each other, a spring 90, Figure 13, is coiled about the ends of the hub 82 of the fuse link extracting member 78. The intermediate portion 91 of the spring 90 is looped about the fuse link extracting member 78 while its ends 92 are hooked over the web 89 interconnecting the ears 86 of the operating member 79. Prior to the installation of the fuse link 46 in operative position in the fuse tube 22, the fuse link extracting member 78 and the operating member 79 are free to rotate together as a unit about the pin 77 relative to the toggle member 62. When the fuse link 46 is installed and the flexible lead 55 is clamped to the toggle member 62 by the clamp nut 70, as shown in Figure 8 of the drawings, then the fuse link extracting member 78 is held stationary with respect to the fuse tube 22, as previously indicated and as shown in Figure 1 of the drawings, and the spring 90 holds the operating member 79 in engagement therewith. As yet, the spring 90 has not been further stressed, so that the fuse link 46 is installed by the lineman under little or no tension, there being no force tending to turn the fuse link extracting member 78 and tension the fuse link 46.

After the fuse link 46 has been installed in the fuse tube 22 under little or no tension, the fuse device 21 is then ready to be inserted in the lower line terminal 15 in the manner previously described. The fuse tube 22 is then rotated to the circuit closed position. Since the fuse link extracting member 78 is held stationary with respect to the fuse tube 22 by the flexible lead 55 of the fuse link 46, it rotates with the fuse tube. The operating member 79 likewise tends to rotate, but its shoulders 87 promptly engage the shoulders 88 on the lower line terminal 15, and further movement thereof is arrested. Moreover, the fuse link extracting member 78 continues to rotate and, in so doing, stresses further the spring 90 interconnecting the two members. It will be clear that the amount that the spring 90 is further stressed depends entirely upon how far the fuse link extracting member 78 is moved relative to the operating member 79. Since this is determined by the design of the lower line terminal 15 and the position of the shoulders 87 on the operating member 79, it will be obvious that the fuse link 46 will always be tensioned in a predetermined amount. This can be varied by changing the relative positions of the shoulders 87 and 88. However, the lineman has nothing to do with the amount of tension that is applied to the fuse link 46. Nothing is left up to his judgment as to how much tension to apply to it.

Now, when the fuse link 46 blows, the operat-

ing member 79 is held stationary and the fuse link extracting member 78 is urged toward it by the spring 90. As previously described, this not only serves to withdraw the remaining portion 5 of the flexible lead 55, but also it serves to break the toggle and initiate the movement of the fuse tube 22 from the circuit closed position.

In Figure 5 of the drawings, the first stage in the movement of the fuse link extracting member 78 is shown. Here the flexible lead 55 has been withdrawn from the fuse tube 22 and the hammer portion 83 has just engaged the anvil or flange 84 of the toggle member 62. As yet, no movement of the fuse tube 22 has taken place. In this position it will be noted that the fuse link extracting member 78 still has some distance to go before it engages the edge 93 of the web 89 of the operating member 79. This further extent of movement corresponds to additional stress in the spring 90 which is capable of urging the toggle member 62 to the unlocked position, in addition to the force exerted by the hammer blow on the anvil or flange portion 84, resulting from the inertia of the fuse link extracting member 78. In the event that the reaction on the fuse tube 22 due to the expulsion action is such that the impact of the fuse link extracting member 78 is not sufficient to break the toggle joint, then after the expulsion action has ceased, the additional stress capable of being exerted by the spring 90 is sufficient alone to break the toggle joint.

In Figure 6 of the drawings the toggle member 62 is shown after it has been operated past the center position and into the unlocked position. When the fuse link extracting member 78 engages the edge 93 of the web 89, the spring 90 is not further capable of effecting relative movement between the fuse link extracting member 78 and the operating member 79. As soon as the toggle member 62 is moved past the center position, the pin 60 is lowered so that the fuse tube 22 is not only swung outwardly but also is moved downwardly from underneath the sleet hood 33 and is thereby unlatched therefrom. The upper end of the fuse device 21 then follows along the arc indicated at 94 in its movement to the open circuit position.

Since the shoulders 87 of the operating member 79 engage the shoulders 88 on the lower line terminal 15 in a vertical plane, the reaction on the trunnions 63 is in a horizontal plane and they are urged into pressure contact engagement with the inner surfaces of the upwardly opening U-shaped slots 64. Obviously this serves to improve the interconnection between the toggle member 62 and the lower line terminal 15.

This arrangement of the shoulders 87 and 88 also permits a slight longitudinal movement of the fuse device 21 in the slots 64. The upward movement in the slots 64 is opposed by the downward biasing action applied to the sleet hood 33. This provides a shock absorber action to the recoil of the fuse tube 22 when the fuse link 46 blows. That is, when the fuse link 46 blows there is a tendency for the fuse tube 22 to move upwardly. Under short circuit conditions this recoil force may be relatively great. Rather than to rigidly hold the fuse tube 22 in place, it is preferable to provide the shock absorber action just described in order to permit some movement of the fuse tube 22 to more readily overcome the recoil and prevent the fuse tube 22 from being torn loose from its supports.

75 The upward movement of the fuse tube 22 is

limited by flanges 96, Figures 1, 2 and 7, which extend inwardly from opposite sides of the housing of the lower line terminal 15 and project into the path of shoulders 97, Figures 8 and 9, on the toggle member 62. Thus, the fuse tube 22 is permitted to move upwardly due to the recoil resulting from the blowing of the fuse link 45 until the shoulders 97 engage the flanges 96.

The movement of the contact fingers 66 outwardly is limited by flanges 98, Figures 2 and 7. The flanges 98 are formed integrally with the housing of the lower line terminal 15 so that they project into the paths of the contact fingers 66 as they are urged outwardly by the leaf springs 67.

It will be observed that the upper portion of the lower line terminal 15, Figure 7, has a downwardly curved roof portion 99 which serves to protect the mechanism therein, and the parts associated with the lower fuse tube terminal 56, from the weather and particularly from the entrance of snow and sleet. The roof portion 99 is formed to provide a groove 100 through which the upper portion of the eye 73 on the toggle member 62 moves when the fuse tube 22 is moved to the circuit closed position. This serves to guide the upper fuse tube terminal 25 into the sleet hood 33.

If desired, the toggle member 62 may be locked against rotation with respect to the ears 61 of the ferrule 51. In such case, a non-dropout fuse construction would be provided. However, the fuse link 46 would be inserted as described hereinbefore and connected in place under little or no tension. When the fuse tube 22 would be rotated to the closed circuit position, the fuse link 46 would be tensioned as before. However, when the fuse link 46 subsequently blows, the fuse link extracting member 78 would perform a single function only, namely, it would withdraw the remaining portion of the flexible lead 55. In some instances, where a non-dropout fuse device is desired, such an arrangement can be employed.

While the upwardly opening U-shaped slots 64 have been shown as being formed in the lower line terminal 17 itself, it will be apparent that these slots could be mounted on a separate support member if desired. Thus, there may be upper and lower line terminals and a support member in which the drop-out fuse device 21 is rotatably mounted.

It will now be apparent that the present invention employs the resilient action of the upper contact member to provide contact pressure, resilient recoil on short circuit operation and latching action. However, the design is such that the tension imposed on the fuse link is substantially independent of this pressure. The linkage is normally on dead center. No shock is transmitted to the fuse link from the upper contact member on operation to the closed circuit position. The tension imposed on the fuse link is not dependent on close adjustment of the spacing of the line terminals.

The fuse link extracting member or rotary flipper extracts the flexible lead or cable from the fuse tube on low current faults at a speed which is unaffected by the mass of the tube assembly or friction at the latching means since the fuse tube and latching means are not required to move during this stage of operation. As a matter of fact the mass of the tube prevents overlapping of the stage and the following stage of operation.

Since the toggle latch is not broken while the flexible lead or cable is being extracted and the arc drawn and extinguished in the fuse tube, the fuse tube remains in place and no arcing occurs at the upper contact member. This operation takes place because the action of the flipper or fuse link extracting member initially is independent of the toggle.

On the continued movement of the fuse link 10 extracting member or flipper its kinetic energy is utilized to break the toggle latch in a second stage of operation. This unlatches the tube and permits the dropout action to take place. The impact of the flipper is useful in breaking a frozen or sleet covered mechanism as will be readily apparent.

In the case of a heavy fault current the reaction of the tube prevents breaking of the toggle by the impact of the flipper. The toggle is finally broken after the current has been interrupted and the gas pressure has subsided by the continued rotation of the flipper as driven by its spring.

As indicated provision is made to permit a sliding recoil of the fuse tube in cooperation with the biased sleet hood. This motion must be limited because of the guiding cam surfaces on the lower contact member. The resilient motion of the sleet hood is limited to prevent parting and arcing at the upper contact member when heavy currents are interrupted. It is desirable to back the tube by a final stop on the upper contact member in order to avoid placing the tube assembly in longitudinal tension which might unduly stress the tube and the ferrule joints.

The dropout fuse device 1, shown in Figure 1 of the drawings and described hereinbefore, can be employed as a part of a repeating fuse construction. In such a construction two or more 40 of the dropout fuse devices are provided, with one of them normally connected in the circuit. When this fuse device blows it is automatically operated to the open circuit position as described, and in so doing it effects the operation of a 45 trans-fer switch which connects the next fuse device in the circuit. Ordinarily, each of the fuse devices that is employed is of the dropout type. However, if desired, the last fuse device need not be of this type.

50 Two or more fuse devices may be employed in a repeating fuse construction. In Figure 14 of the drawings, three dropout fuse devices of the type shown at 1 in Figure 1 of the drawings have been shown as assembled in a repeating fuse construction. If desired, only two of the dropout fuse devices may be employed or more than three can be used, as will be readily understood.

The three dropout fuse devices 1 are arranged to be mounted commonly on a suitable support 60 member such as a channel member 102 having spaced apertures 103 to permit mounting of the same on a suitable support structure. Each of the insulators 2 of the dropout fuse devices 1 is provided with the clamp band 3, as previously 65 described. However, the bracket 6 is omitted and instead two L-shaped brackets 104 are substituted therefor. These brackets 104 are secured to the clamp band 3 by the bolts 4 and 5, as shown in Figure 15 of the drawings. Also, as shown in this figure, the outturned ends of the brackets 104 are secured to the channel 102 by suitable bolts 105.

The upper line terminals 9 are commonly connected together by a connector strap 106 of good

conducting material such as copper. The strap 106 is secured to each of the line terminals 11 by means of a suitable connector 107 which fits over the ribs 13. One line conductor is connected to one of the connectors 107 so that the upper line terminals 9 are commonly connected thereto. The other line conductor is connected to the lower line terminal 15 of the left hand fuse device 1 as previously described.

The strap 106 not only serves to interconnect the upper line terminals 11 but also it serves to mechanically tie the dropout fuse devices 1 together in order to more rigidly mount the same.

With a view to connecting the next dropout fuse device into the circuit when the preceding fuse device blows, transfer switches, shown generally at 108, are provided. It will be noted that a transfer switch assembly is provided between the first and second fuse devices and between the second and third fuse devices.

Each of the transfer switch assemblies 108 comprises a switch arm or switch blade 109 that is rotatably mounted on a stud 110 coaxially with the associated fuse tube 22. That is, each of the studs 110 is coaxial with the trunnions 63, Figure 1, so that each fuse tube 22 and its associated switch arm or blade 109 rotate about a common axis. The stud 110 is carried by a bracket 111 which may be secured by suitable screws to one side of the housing forming the lower line terminal 15. Each switch arm or blade 109 is provided with an extension or contact arm 112 for movement into and out of contact engagement with a stationary contact assembly, shown generally at 113. The stationary contact assembly 113 is carried by a bracket 114 that is secured by means of suitable screws to the housing forming a part of the lower line terminal 15 of the next fuse device.

With a view to operating the switch arm or blade 109 to the circuit closed position when the first fuse device blows, an arm 115 is provided thereon which extends into the path of the fuse tube 22 in its movement to the open circuit position. As shown in Figure 14 of the drawings, the left-hand dropout fuse device 1 has been operated to the open circuit position. In so doing it has picked up the arm 115 and moved the switch arm or blade 109 so that the contact arm 112 carried thereby engages the stationary contact assembly 113, thereby connecting the center fuse device into the circuit.

When the blown fuse link in the fuse device which has operated has been replaced and the fuse device restored to service, the transfer switch should be operated in a reverse manner in order to disconnect the next fuse device from the circuit. This is accomplished automatically by the provision of an arm 116 on the other end of the switch arm or blade 109 also in the path of movement of the fuse tube 22. When the fuse tube 22 is operated to the circuit closed position, it engages the arm 116 and carries with it the switch arm or switch blade 109. As a result, the contact engaging member 112 is moved out of engagement with the stationary contact assembly 113.

As shown in Figure 16 of the drawings, the switch arm or blade 109 is provided with an eye 117 to permit operation by means of a switch stick. When the prong of the switch stick is inserted in the eye 117, the switch arm or blade 109 can be moved, provided such movement is

not prevented by the fuse tube associated therewith.

As illustrated in Figure 17 of the drawings, the contact arm 112 of the switch arm or blade 109 is provided with a generally cylindrical contact engaging portion 118 for interfitting between the inturned ends 119 of a generally U-shaped bifurcated straplike contact member 120. The ends 119 are urged inwardly by means of a generally U-shaped spring member 121. Portions of the contact member 120 are flared outwardly as indicated at 122 in order to facilitate the entry of the contact engaging member 118. The contact member 120 and its associated spring 121 are mounted in a downwardly opening housing 123 by means of screws 124 which project therethrough and through a suitable plate 125 that is secured to the members 120 and 121 by means of a rivet 126.

It is desirable that the switch arm or blade 109 remain in any position to which it is operated. This is accomplished by mounting it on the stud 110 in such manner as to provide a predetermined amount of friction therebetween. As shown in Figure 18 of the drawings, the stud 110 may be knurled at one end and secured in the bracket 111 by a press fit. The knurling is indicated at 128. The stud 110 is provided with a flanged portion having a generally conical surface 129 for engagement by a correspondingly shaped surface on the switch arm or blade 109. These conical surfaces are urged into mutual engagement by means of a coil compression spring 130 which surrounds the stud 110, as shown, and is held in position by means of a washer 131 that is restrained by a nut 133. The nut 133 is provided with a conical surface 134 for engaging a correspondingly shaped surface on the washer 131. This construction not only provides a definite frictional force for holding the switch arm or blade 109 in any position to which it may be operated, but also it permits adjustment of the friction by changing the position of the nut, 133, as will be readily understood.

Since certain further changes can be made in the foregoing constructions, and different embodiments of the invention can be made without departing from the scope thereof, it is intended that all matter shown in the accompanying drawings or described hereinbefore shall be interpreted as illustrative and not in a limiting sense.

What is claimed as new is:

1. A circuit interrupter comprising, in combination, a fuse tube adapted to receive a fuse link, means for tensioning the fuse link, means for holding the fuse link in operative relation to the link tensioning means with little or no application of tension to the fuse link, and means for stressing said link tensioning means to tension the fuse link.

2. A circuit interrupter comprising, in combination, a fuse tube adapted to receive a fuse link, link tensioning means movable through a predetermined extent for tensioning the fuse link, means for holding the fuse link in operative relation to said link tensioning means with little or no tension being applied to the fuse link, and means for moving said link tensioning means through said predetermined extent to apply a predetermined tension to the fuse link.

3. A circuit interrupter comprising, in combination, terminal members and means for mounting the same in insulated spaced relation, a fuse tube having terminals for contact engagement

with said terminal members in the circuit closed position and adapted to receive a fuse link for interconnecting said terminals, means for pivotally supporting said fuse tube, means for tensioning the fuse link, means for holding the fuse link in operative relation to the link tensioning means with little or no application of tension to the fuse link, and means operative on movement of said fuse tube to the circuit closed position for stressing said link tensioning means to tension the fuse link.

4. A circuit interrupter comprising, in combination, terminal members and means for mounting the same in insulated spaced relation, a fuse tube having terminals for contact engagement with said terminal members in the circuit closed position and adapted to receive a fuse link for interconnecting said terminals, means for pivotally supporting said fuse tube, link tensioning means movable through a predetermined extent for tensioning the fuse link, means for holding the fuse link in operative relation to said link tensioning means with little or no tension being applied to the fuse link, and means operative on pivotal movement of said fuse tube to the circuit closed position for moving said link tensioning means through said predetermined extent to apply a predetermined tension to the fuse link.

5. A circuit interrupter comprising, in combination, a fuse tube adapted to receive a fuse link, a pair of relatively movable members carried by said fuse tube and biased for movement toward each other, means for holding the fuse link in operative relation to one of said movable members under little or no tension, and means for relatively moving said movable members apart for placing the same under stress and tensioning the fuse link.

6. A circuit interrupter comprising, in combination, terminal members and means for mounting the same in insulated spaced relation, a fuse tube having terminals for contact engagement with said terminal members in the circuit closed position and adapted to receive a fuse link for interconnecting said terminals, means for pivotally supporting said fuse tube, a pair of relatively movable members carried by said fuse tube and biased for movement toward each other, means for holding the fuse link in operative relation to one of said movable members under little or no tension, and means operative on pivotal movement of said fuse tube to the circuit closed position for relatively moving said movable members apart to place the same under stress and thereby tension the fuse link.

7. A circuit interrupter comprising, in combination, a fuse tube adapted to receive a fuse link, a pair of members coaxially pivotally mounted on said fuse tube over which the fuse link is disposed to be placed, spring means biasing said members toward each other, means for holding the fuse link in operative relation to one of said members under little or no tension, and means for relatively moving said members apart to stress said spring means and thereby tension the fuse link.

8. A circuit interrupter comprising, in combination, terminal members and means for mounting the same in insulated spaced relation, a fuse tube having terminals for contact engagement with said terminal members in the circuit closed position and adapted to receive a fuse link for interconnecting said terminals, means for pivotally supporting said fuse tube, a pair of members coaxially pivotally mounted on

5 said fuse tube over which the fuse link is disposed to be placed, spring means biasing said members toward each other, means for holding the fuse link in operative relation to one of said members under little or no tension, and means operative on pivotal movement of said fuse tube to the circuit closed position for relatively moving said members apart to cock said spring means and thereby tension the fuse link.

9. A circuit interrupter comprising, in combination, upper and lower line terminals and means for mounting the same in insulated spaced relation, latch means associated with said upper line terminal, support means associated with said lower line terminal, a fuse tube having terminals at its ends for engaging said line terminals and adapted to receive a fuse link for interconnecting the fuse tube terminals, toggle means pivoted on said support means and on said fuse tube and adapted to be held rigid therewith as long as the fuse link remains intact and swingable therewith to the circuit closed position where said fuse tube is held by said latch means, and means restrained by the fuse link and released on blowing of the same for striking said toggle means to insure breaking of the toggle and disengagement of said fuse tube from said latch means.

10. A circuit interrupter comprising, in combination, upper and lower line terminals and means for mounting the same in insulated spaced relation, latch means associated with said upper line terminal, support means associated with said lower line terminal, a fuse tube having terminals at its ends for engaging said line terminals and adapted to receive a fuse link for interconnecting the fuse tube terminals, toggle means pivoted on said support means and on said fuse tube and adapted to be held rigid therewith as long as the fuse link remains intact and swingable therewith to the circuit closed position where said fuse tube is held by said latch means which exerts a downward thrust thereon, the locations of the two pivot axes of said toggle means in the circuit closed position with respect to the direction of downward thrust of said latch means being such that the toggle means is slightly over-center or locked, and means restrained by the fuse link and released on blowing of the same for impacting said toggle means to move the same from the over-center or locked position and lower said fuse tube out of engagement with said latch means.

11. A circuit interrupter comprising, in combination, upper and lower line terminals and means for mounting the same in insulated spaced relation, latch means associated with said upper line terminal, support means associated with said lower line terminal, a fuse tube having terminals at its ends for engaging said line terminals and adapted to receive a fuse link for interconnecting the fuse tube terminals, a toggle member pivoted on said support means and on said fuse tube and adapted to be held rigid therewith as long as the fuse link remains intact and swingable therewith to the circuit closed position where said fuse tube is held by said latch means, an operating member and a fuse link extracting member pivotally mounted on said toggle member and biased toward each other by spring means, said fuse link extracting member being initially operatively associated with the fuse link and applying thereto little or no tension, and means for arresting movement of said operating member while said fuse tube is being moved to the circuit closed position and said fuse link ex-

tracting member is held by the fuse link substantially stationary with respect to said fuse tube whereby said spring means is stressed and the fuse link is tensioned in an amount depending upon the relative movement apart of said fuse link extracting and operating members during the circuit closing operation, said fuse link extracting member being released on blowing of the fuse link and withdrawing a portion of the same from said fuse tube and impacting said toggle member to insure breaking of the toggle and disengagement of said fuse tube from said latch means.

12. A circuit interrupter comprising, in combination, terminal members and means for mounting the same in insulated spaced relation, a fuse tube having terminals for contact engagement with said terminal members in the circuit closed position and adapted to receive a fuse link for interconnecting said terminals, means for pivotally supporting said fuse tube, a fuse link extracting member and an operating member coaxially pivotally mounted on said fuse tube about its pivotal axis, spring means biasing said members toward each other, means for holding the fuse link in operative relation to said fuse link extracting member under little or no tension, and means for arresting the movement of said operating member on movement of said fuse tube to the circuit closed position whereby said spring means is stressed and the fuse link is tensioned in an amount depending upon the relative movement apart of said fuse link extracting and operating members during the circuit closing operation.

13. A circuit interrupter comprising, in combination, upper and lower terminals and means for mounting the same in insulated spaced relation, a fuse tube having terminals at its ends for contact engagement with said upper and lower terminals and adapted to receive a fuse link for interconnecting the fuse tube terminals, means pivotally mounting said fuse tube on said lower terminal, a fuse link extracting member and an operating member coaxially pivotally mounted on said fuse tube about its pivotal axis on said lower terminal, spring means biasing said members toward each other, means for holding the fuse link in operative relation to said fuse link extracting member initially under little or no tension, and means on said lower terminal for arresting the movement of said operating member while said fuse tube is being moved to the circuit closed position and said fuse link extracting member remains substantially stationary with respect to said fuse tube whereby said spring means is stressed and the fuse link is tensioned in an amount depending upon the relative movement apart of said fuse link extracting and operating members during the circuit closing operation, said fuse link extracting member being released on blowing of the fuse link and withdrawing a portion of the same from said fuse tube in its movement under the influence of said spring means toward said operating member.

14. A circuit interrupter comprising, in combination, upper and lower line terminals and means for mounting the same in insulated spaced relation, a fuse tube having upper and lower terminals at its ends for contact engagement with said line terminals and adapted to receive a fuse link for interconnecting the fuse tube terminals, a toggle member pivotally mounted on said fuse tube at its lower end and also pivotally mounted on said lower line terminal, a fuse

link extracting member and an operating member pivotally mounted on said toggle member, spring means biasing said fuse link extracting and operating members toward each other, means on said toggle member for holding the fuse link in operative relation to said fuse link extracting member initially under little or no tension, and stop means on said lower line terminal for arresting movement of said operating member while said fuse tube is being moved to the circuit closed position and said fuse link extracting member is held by the fuse link substantially stationary with respect to said fuse tube whereby said spring means is stressed and the fuse link is tensioned in an amount depending upon the relative movement apart of said fuse link extracting and operating members during the circuit closing operation, said fuse link extracting member being released on blowing of the fuse link and withdrawing a portion of the same from said fuse tube in its movement under the influence of said spring means toward said operating member.

15. A circuit interrupter comprising, in combination, upper and lower line terminals and means for mounting the same in insulated spaced relation, latch means associated with said upper line terminal, a fuse tube having terminals at its ends for engaging said line terminals and adapted to receive a fuse link for interconnecting the fuse tube terminals, a toggle member pivotally mounted on said lower line terminal and pivotally connected to said fuse tube and adapted to be held rigid therewith as long as the fuse link remains intact and swingable therewith to the circuit closed position where said fuse tube is held by said latch means, and means carried by said fuse tube for tensioning the fuse link as a result of movement of said fuse tube to the circuit closed position, the tension imposed on the fuse link being transmitted through the lower fuse tube terminal to said lower line terminal to provide pressure contact engagement therebetween.

16. A circuit interrupter comprising, in combination, upper and lower line terminals and means for mounting the same in insulated spaced relation, latch means associated with said upper line terminal, a fuse tube having terminals at its ends for engaging said line terminals and adapted to receive a fuse link for interconnecting the fuse tube terminals, said lower line terminal having generally U-shaped upwardly opening terminal receiving means, a toggle member pivotally and detachably mounted in said terminal receiving means and pivotally connected to said fuse tube and adapted to be held rigid therewith as long as the fuse link remains intact and swingable therewith to the circuit closed position where said fuse tube is held by said latch means, and means carried by said fuse tube for tensioning the fuse link as a result of movement of said fuse tube to the circuit closed position, the tension imposed on the fuse link being transmitted through said toggle member to the inner surface of said U-shaped terminal receiving means to provide pressure contact engagement therebetween.

17. A circuit interrupter comprising, in combination, a pair of line terminals and means for mounting the same in insulated spaced relation, a fuse tube having terminals at its ends for engaging said line terminals and adapted to receive a fuse link for interconnecting the fuse tube terminals, a pair of relatively movable mem-

bers carried by said fuse tube and biased for movement toward each other, means for holding the fuse link in operative relation to one of said movable members under little or no tension, means for pivotally mounting said fuse tube relative to said line terminals, and means cooperating with the other of said pair of relatively movable members for arresting movement of the same while said fuse tube is being swung into circuit closed position whereby the fuse link is tensioned.

18. A circuit interrupter comprising, in combination, upper and lower line terminals and means for mounting the same in insulated spaced relation, a fuse tube having terminals at its ends for engaging said line terminals and adapted to receive a fuse link for interconnecting the fuse tube terminals, said lower line terminal having a pair of generally U-shaped upwardly opening terminal receiving portions, a toggle member having a pair of trunnions for positioning in said terminal receiving portions and pivotally connected to said fuse tube and adapted to be held rigid therewith by the fuse link being connected thereto, an operating member and a fuse link extracting member pivotally mounted on said toggle member, spring means biasing said operating and extracting members toward each other, said fuse link extracting member being initially operatively associated with the fuse link and applying thereto little or no tension, and stop means on said lower line terminal positioned in the path of said operating member for arresting movement of the same while said fuse tube is being moved to the circuit closed position and said fuse link extracting member is held stationary with respect to said fuse tube whereby said spring means is stressed and the fuse link is tensioned, the stress of said spring means being transmitted through said trunnions to the inner surfaces of said U-shaped terminal receiving portions to provide pressure contact engagement therebetween.

19. A circuit interrupter comprising, in combination, upper and lower line terminals and means for mounting the same in insulated spaced relation, latch means associated with said upper line terminal, a fuse tube having terminals at its ends for engaging said line terminals and adapted to receive a fuse link for interconnecting the fuse tube terminals, said lower line terminal having generally U-shaped upwardly opening terminal receiving means, a toggle member pivotally and detachably mounted in said terminal receiving means and pivotally connected to said fuse tube and adapted to be held rigid therewith as long as the fuse link remains intact and swingable therewith to the circuit closed position where said fuse tube is held by said latch means, means carried by said fuse tube for tensioning the fuse link as a result of movement of said fuse tube to the circuit closed position, the tension imposed on the fuse link being transmitted through said toggle member to the inner surface of said U-shaped terminal receiving means to provide pressure contact engagement therebetween, resilient means cooperating with said upper line terminal and urging said fuse tube downwardly, the recoil of said fuse tube on blowing or the fuse link therein causing the fuse tube to move upwardly against the biasing force of said resilient means thereby providing a shock absorber action, and means limiting the upward movement of said fuse tube due to said recoil.

20. A circuit interrupter comprising, in combination, upper and lower line terminals and means for mounting the same in insulated spaced relation, a fuse tube having terminals at its ends for engaging said line terminals and adapted to receive a fuse link for interconnecting the fuse tube terminals, said lower line terminal having a pair of generally U-shaped upwardly opening terminal receiving portions, a toggle member having a pair of trunnions for positioning in said terminal receiving portions and pivotally connected to said fuse tube and adapted to be held rigid therewith by the fuse link being connected thereto, an operating member and a fuse link extracting member pivotally mounted on said toggle member, spring means biasing said operating and extracting members toward each other, said fuse link extracting member being initially operatively associated with the fuse link and applying thereto little or no tension, stop means on said lower line terminal positioned in the path of said operating member for arresting movement of the same while said fuse tube is being moved to the circuit closed position and said fuse link extracting member is held stationary with respect to said fuse tube whereby said spring means is stressed and the fuse link is tensioned, the stress of said spring means being transmitted through said trunnions to the inner surfaces of said U-shaped terminal receiving portions to provide pressure contact engagement therebetween, resilient means cooperating with said upper line terminal and urging said fuse tube downwardly, the recoil of said fuse tube on blowing of the fuse link therein causing the fuse tube to move upwardly against the biasing force of said resilient means thereby providing a shock absorber action, and means limiting the upward movement of said fuse tube due to said recoil.

21. A circuit interrupter comprising, in combination, upper and lower line terminals and means for mounting the same in insulated spaced relation, a fuse tube having upper and lower terminals at its ends for contact engagement with said line terminals and adapted to receive a fuse link for interconnecting the fuse tube terminals, a toggle member pivotally mounted on said fuse tube at its lower end and also pivotally mounted on said lower line terminal, a fuse link extracting member and an operating member pivotally mounted on said toggle member, spring means biasing said fuse link extracting and operating members toward each other, means on said toggle member for holding the fuse link in operative relation to said fuse link extracting member initially under little or no tension, stop means on said lower line terminal for arresting movement of said operating member while said fuse tube is being moved to the circuit closed position and said fuse link extracting member is held by the fuse link substantially stationary with respect to said fuse tube whereby said spring means is stressed and the fuse link is tensioned in an amount depending upon the relative movement apart of said fuse link extracting and operating members during the circuit closing operation, said fuse link extracting member being released on blowing of the fuse link and withdrawing a portion of the same from said fuse tube in its movement under the influence of said spring means toward said operating member, and means on said toggle member in the path of said fuse link extracting member and adapted to be struck thereby when it is released on blowing of the fuse

link prior to engagement with said operating member for breaking the toggle by positively initiating rotation of said toggle member.

22. A circuit interrupter comprising, in combination, upper and lower line terminals and means for mounting the same in insulated spaced relation, a fuse tube having terminals at its ends for engaging said line terminals and adapted to receive a fuse link for interconnecting the fuse tube terminals, said lower line terminal having a pair of generally U-shaped upwardly opening terminal receiving portions, a toggle member having a pair of trunnions for positioning in said terminal receiving portions and pivotally connected to said fuse tube and adapted to be held rigid therewith by the fuse link being connected thereto, an operating member and a fuse link extracting member pivotally mounted on said toggle member, spring means biasing said operating and extracting members toward each other, said fuse link extracting member being initially operatively associated with the fuse link and applying thereto little or no tension, and stop means on said lower line terminal located in the path of said operating member in such position as

5 to arrest movement of the same while said fuse tube is being moved to the circuit closed position and said fuse link extracting member is held stationary with respect to said fuse tube so that the reaction to the stressing of said spring means resulting from the movement apart of said operating and extracting members is transmitted through said trunnions in a substantially horizontal plane against the rear inner surfaces of

10 said U-shaped terminal receiving portions.

15 23. A circuit interrupter comprising, in combination, upper and lower line terminals and means for mounting the same in insulated spaced relation, a fuse device for interconnecting said terminals and means for pivotally mounting the same at its lower end, a sleet hood pivotally mounted on said upper line terminal and arranged to latch said fuse device in circuit closed position, a flange depending from said sleet hood having an aperture, and a stop extending from said upper terminal into said aperture for limiting the up and down movement of said sleet hood.
